TEMPERATURE CONTROL SYSTEM FOR
OVENS HEATED BY HYDROCARBON
BURNERSEarl Hillebrand, Albert Lea, Minn., assignor to
American Gas Machine Company, Inc., Albert
Lea, Minn., a corporation of DelawareApplication March 20, 1935, Serial No. 11,992
Renewed May 24, 1937

5 Claims. (Cl. 236—15)

This invention relates to ovens wherein the heating medium is supplied by means of a hydrocarbon burner and more particularly to a system for generating and feeding the mixed fuel to the oven burner in such manner that the temperature within the oven may be maintained at various desired temperatures within a given range.

It is an object of my invention to provide a system adapted for association with conventional types of hydrocarbon generators whereby the amount of mixed fuel admitted to the oven burner is controlled by heat responsive mechanism dependent upon the temperature within an oven.

It is a further object to provide a system and apparatus of the class above referred to wherein the apparatus may be adjusted to maintain various predetermined temperatures within the oven within a relatively wide range.

More specifically it is an object to provide such a system wherein a main generating tube and an auxiliary or pilot generating tube are both subjected to heat from a generating burner and wherein mechanism controlled by the temperature within the oven is supplied for cutting in or out the supply of liquid fuel to the main generating tube in order to vary the amount of mixed fuel admitted to the oven burner as required to maintain the oven temperature at the desired predetermined point.

These and other objects and advantages of the invention will be more fully set forth in the following description made in connection with the accompanying drawing, in which like reference characters refer to similar parts throughout the several views, and in which:—

Fig. 1 is a more or less diagrammatical perspective view showing an embodiment of my invention and operatively associated with a suitable hydrocarbon generator and with an oven and oven burner, and

Fig. 2 is a vertical section taken longitudinally through a suitable form of heat responsive fuel control mechanism utilized in my system.

As shown in the drawing, my improved oven temperature control system and fuel feeding system is associated with a hydrocarbon generator which may be of any suitable type. The generator illustrated is of the general type disclosed in the co-pending application of Hans C. Hanson and Walter Olsen, S. N. 694,082, filed October 18, 1933, and a detailed description thereof is thought unnecessary. The generator includes a generating burner B connected with a manifold M, which manifold receives the combustible mixture from a conduit C communicating at its upper end with

a mixing chamber X. Mixing chamber X has extending therein the delivery end or ends of fuel generating means and is further provided with an air intake opening, not shown.

A portion of the wall O defining an oven is shown in Fig. 1 and an oven burner OB is mounted in the lower part of the oven connected by a conduit 3 with the fuel mixing manifold M.

Valve mechanism Y for controlling flow of fuel and air to the burner for starting purposes is associated with the generator but has no cooperative relationship with the apparatus of my present invention.

In my control system I prefer to utilize a pair of generating tubes 4 and 5, both of which communicate at their rear ends with the interior of mixing chamber X terminating in very small nozzles having injector effect, which are disposed inwardly of the front wall of chamber X. The main generator tube 4 has greater capacity and a nozzle orifice of substantially greater size than the auxiliary or pilot generator tube 5, the discharge orifice of which is restricted so that it may only discharge a very small spray of fuel. Shut off valves 6 and 7 of conventional type are provided for generator tubes 4 and 5 respectively. The liquid fuel line 8 from the supply tank connects with a branch fitting 9, one leg of which is connected by a pipe 10 with the auxiliary or pilot generator 5. The other leg or branch of fitting 9 is connected with the intake passage 11a of a temperature responsive feed controlling mechanism indicated as an entirety by the letter T. Said mechanism includes a valve body 11 mounted in a suitable casing 12 as shown of cylindrical form and having connection nipples which form or assist in forming the intake passage 11a and outlet passage 11b, said nipples being horizontally aligned and extending through a slot 12a formed in the top of casing 12 to permit slight relative longitudinal movement of valve body 11 within casing 12 as will later more fully appear. The outlet nipple and passage 11b is connected by pipe 13 with the forward end of main generator tube 4.

Within valve body 11 and extending axially thereof is a relatively large communicating passage 11c forming a valve chamber with one end of which intake passage 11a communicates and with the other end of which the outlet passage 11b communicates, it being noted that as shown outlet passage 11b communicates with passage 11c axially thereof to provide an axially disposed valve seat with which a plug type valve 14 is adapted to cooperate. Valve 14 has an enlarged head which slidably fits within the cylindrical

walls of chamber 11c and is urged away from its seat by means of a coiled compression spring 15 surrounding the body of the valve. It will be obvious that when valve 14 is in open position as shown in Fig. 2, liquid fuel will pass through inlet passage 11a through the communicating passage or chamber 11c and out of the valve body through outlet passage 11b and then through pipe 13 into the main generating tube 4. The head of valve 14 abuts against an air-tight diaphragm 16 mounted behind the valve and the flexing of said diaphragm and longitudinal movement of valve 14 is effected by means of an abutment plug 17 slidably mounted in a cup 18 which is fixed to the movable end of an expandable member or bellows 19 of the sylphon type. Cup 18 is slidably mounted in a plug fitting 20 which as shown is screwed axially into the rear end of valve body 11 and which also acts to retain diaphragm 16 in operative position. Compression spring 18a is interposed between abutment plug 17 and cup 18 to yieldingly hold the abutment plug in extended position. Bellows 19 is connected by a small conduit 21 with a closed tube 22 mounted in the upper portion of the oven O, and tube 22, conduit 21 and bellows 19 are filled with a heat expansive fluid. The closed tube 22 is preferably constructed of heat conductive material, such as copper, or silver.

30 The compression spring 18a takes up any excess movement of abutment plug 17 due to continued expansion of the bellows 19 after valve 14 has been closed. Spring 15, of course, is adapted to unseat the valve when bellows 19 contracts beyond a predetermined point.

To adjust the setting of my apparatus for various predetermined temperatures within oven O, I provide an adjustment screw 23 having threaded engagement with a heavy plug 24 at the 40 forward end of cylindrical casing 12 and the inner end of which abuts against the forward end of valve body 11 and therefore effects longitudinal movement of the valve body relatively to the valve 14 mounted therein. The outer end of 45 adjustment screw 23 is provided with a manipulating knob 25 which carries a graduated disk 25a having radially disposed graduations thereon which may be caused to register with a stationary indicator or pointer 26 which may be conveniently affixed to the forward end of casing 12.

In operation the generator burner B is started at which time the oven O is cool and valve 14 is then removed from its seat in communication with passage 11b. Liquid fuel from the source of supply then passes through the line 8 into the valve body through inlet passage 11a through communicating passage or chamber 11c and out of the valve body through outlet passage 11b and into the main generating tube through conduit 13. 60 Oven burner OB may be supplied with combustible fuel by opening valve V and may be lighted. Until the oven reaches a predetermined temperature, liquid fuel will continue to pass through the valve body of the temperature responsive mechanism and into the main generating tube. Some small amount of fuel may also pass through the auxiliary or pilot generator tube 5, but because of the small orifice of the same, most of the fuel or combustive mixture will pass 65 through the main generator until valve 14 is closed.

The expansion of fluid in the closed tube 22 within the oven in turn expands bellows 19, moving cup 18 and the abutment plug 17 yieldingly 70 carried thereby toward the valve seat and there-

by longitudinally moving the valve to closed position and cutting off the flow of liquid fuel to the main generating tube. All fuel supplied to mixing chamber X then must be discharged by the orifice of pilot or auxiliary vaporizing tube 5 and 5 of course the amount of fuel consumed will be relatively small until the temperature of the oven again calls for additional heating medium to maintain the desired predetermined temperature.

From the foregoing description it will be apparent that I have provided a simple, comparatively economical and highly efficient system for maintaining the ovens of hydrocarbon stoves and the like at various predetermined temperatures. It will further be understood that while in the 15 drawing I have illustrated mechanism which supplies only combustible fuel for an oven burner and a generator burner, that numerous other burners may be connected with manifold M as desired.

It will, of course, be understood that various 20 changes may be made in the form, details, proportions and arrangement of the parts, without departing from the scope of my invention, which generally stated, consists in a device capable of carrying out the objects above set forth, and in 25 the novel parts and combinations of parts disclosed and defined in the appended claims.

What is claimed is:—

1. A heating and temperature control system for an oven, having in combination; a hydrocarbon fuel generator comprising a burner, a mixing chamber, and fuel vaporizing means subjected to the heat from said burner and being connected with a source of liquid fuel supply, said means having a pair of discharge elements communicating with said mixing chamber, mechanism for cutting off supply of fuel to one of said elements and means responsive to the temperature of said oven for operating said mechanism to maintain said oven at a substantially predetermined temperature.

2. A heating and temperature control system for an oven, having in combination; a hydrocarbon fuel generator comprising a burner, a mixing chamber, and fuel vaporizing means subjected to the heat from said burner and being connected with a source of liquid fuel supply, said vaporizing means having a pair of discharge elements communicating with said mixing chamber, one being adapted to discharge vaporized fuel at a 40 considerably greater rate of discharge than the other, mechanism for cutting off supply of fuel to said larger capacity element and means responsive to the temperature of said oven for operating said mechanism to maintain said oven 55 at a substantially predetermined temperature.

3. A heating and temperature control system for an oven having in combination; a hydrocarbon fuel generator comprising a burner, a mixing chamber, a pair of fuel vaporizing tubes both subjected to the heat from said burner and both adapted to discharge vaporized fuel into said mixing chamber, means connecting one of said tubes at all times with a source of liquid fuel and means adapted to connect said other tube 65 with said source of liquid fuel, mechanism for connecting and disconnecting said second mentioned tube with said source; an oven having a burner therein connected with the mixing chamber of said generator; and means responsive to the temperature of said oven for operating said mechanism to maintain said oven at a substantially predetermined temperature.

4. A temperature control system for an oven having in combination, a hydrocarbon fuel gen- 75

erator comprising a burner, a main generating tube and an auxiliary generating tube, both of said tubes being mounted in position to be heated by said burner, a mixing chamber having an air entrance and having communication with the delivery ends of both of said generating tubes, a burner for heating said oven connected with said air mixing chamber, a liquid fuel line having a connection with said auxiliary generator, a valve body having a passage therein, one portion of which is connected with said fuel line and another portion of which is connected with said main generator tube, a valve mounted in said body between said connections adapted to close communication between said passage and the connection with said main generator tube and temperature responsive means disposed in said chamber and adapted to control the operation of said valve.

20 5. A heating and temperature control system

for an oven, having in combination; a hydrocarbon fuel generator comprising a burner, a mixing chamber, and fuel vaporizing means subjected to the heat from said burner, said vaporizing means comprising a pair of vaporizing elements, both of which deliver to said mixing chamber, connections between said elements and a source of liquid fuel supply whereby both of said elements may be connected with said source or only one thereof may be connected, a valve for controlling the supply of fuel to one of said elements and means responsive to the temperature of said oven for operating said valve to maintain said oven at a substantially predetermined temperature through control of fuel supply to said respective vaporizing elements and the consequent discharge of vaporizing fuel from said elements to said mixing chamber.
